Primary Examiner — Susan Moon Lee(74) *Attorney, Agent, or Firm* — IPAXIO S.E.N.C.**(57) CLAIM**

The ornamental design for a pet bowl, as shown and described.

DESCRIPTION

FIG. 1 is an isometric view of a pet bowl showing my new design;

FIG. 2 is a top view thereof;

FIG. 3 is a right side view thereof, with the left side view being a mirror image;

FIG. 4 is a front view thereof;

FIG. 5 is a rear view thereof; and,

FIG. 6 is a bottom view thereof, wherein the bottom portion shown in broken lines forms no portion of the claimed ornamental design.
